UNITED STATES PATENT OFFICE.

LUTHER H. TRIESCHMANN, OF HARTFORD, CONNECTICUT.

HOLDER RING OR FRAME.

1,232,626.

Specification of Letters Patent. Patented July 10, 1917.

Application filed July 12, 1915. Serial No. 39,457.

To all whom it may concern:

Be it known that I, LUTHER H. TRIESCHMANN, a citizen of the United States of America, and resident of Hartford, in the county of Hartford and State of Connecticut, have invented certain new and useful improvements in Holder Rings or Frames, of which the following is a full, clear, and exact description.

10 The object of this invention is to provide a holder or key ring that is divided into two portions whereby a key or other article can be kept in a special part separated from the keys or other articles on the ring to be 15 quickly accessible for use when desired.

The invention is described in conjunction with the accompanying drawings and set forth in the claims.

In the accompanying drawings illustrating embodiments of my invention:—

Figure 1 shows in side elevation, and

Fig. 2 in edge elevation, one form of the clip; and

Fig. 3 is a perspective view of the same.

25 In the drawings I show a ring formed of a piece of thin rod or wire 8 that has a reduced or converging portion at 9 in which the end portions 10 and 11 lap each other, and which lapped portions are flattened on their contiguous sides in the plane of the clip.

30 In this particular form the material or sides beyond the said lapped portions are brought into close proximity, or almost into contact, for the purpose of confining keys and the like articles that may be strung onto the ring, at the annular portion 12 beyond the adjacent portions 13 and 14, and which portion 12 is shown as substantially circular.

40 By this arrangement or configuration is formed a comparatively large loop 12, and a smaller loop 14, and the latter can be utilized to hold a special key or other similar device so that when a bunch of keys are arranged 45 on this clip, this particular key or article is segregated from the other keys, so as to be

quickly accessible when desired, without the necessity of having to look through the bunch of keys to find the one that is wanted.

It will be readily understood that the keys or other articles can be attached or removed by separating the lapping portions 10 and 11 to string the key on the smaller loop 14; and then by further separation of the adjacent parts at 13 and 14, the key can be slid up to the larger loop 12, as may be desired.

The smaller loop 14 will also provide a convenient place for attachment to the key chain or other holder, with the special key retained on the smaller loop 14, and the other keys strung on the larger loop portion 12.

I claim:—

1. A key ring consisting of a length of 65 spring wire, the intermediate portion of which is bent around to form almost, but not quite, a complete circle, to serve as a key ring proper, the extremities of the wire being bent to form opposite similarly curved loops and to have the end portions thereof 70 overlapped facewise alongside each other, the spaces within the key ring proper, and the supplemental ring-like portion inclosed by said loops communicating with each other by a very narrow connecting space. 75

2. A key ring consisting of a length of spring wire, the intermediate portion of which is bent around to form almost, but not quite, a complete circle, to serve as the key ring proper, the extremities of the wire 80 being bent to form opposed similarly curved loops and to have the end portions thereof overlapped facewise alongside each other, the overlapped portions of the loops being of reduced thickness and flattened at their 85 contiguous sides, the spaces within the key ring proper and the supplemental ring-like portion inclosed by said loops communicating with each other by a narrow connecting space. 90

Signed by me at Windsor, Conn.

L. H. TRIESCHMANN.
